UNITED STATES PATENT OFFICE.

NELSON P. JOHNSTON, OF ANDERSON, INDIANA.

SWIMMING DEVICE.

1,335,687.

Specification of Letters Patent. Patented Mar. 30, 1920.

Application filed October 13, 1919. Serial No. 330,180.

To all whom it may concern:

Be it known that I, NELSON P. JOHNSTON, a citizen of the United States, residing at Anderson, in the county of Madison and 5 State of Indiana, have invented new and useful Improvements in Swimming Devices, of which the following is a specification.

This invention has reference to a combined swimming and life saving device.

10 The object of the invention is to produce a device of this character which may be readily attached to the person of the user, the same being of a buoyant nature whereby to assist in retaining the user on 15 the surface of the water and being provided with propellers actuated by the movement of the feet of the user whereby a person may be propelled through the water without danger of drowning.

20 A further object of the invention is to produce a swimming and life saving device comprising a flat body having its center formed with a keel and provided with means whereby the flat body may be readily 25 strapped on the trunk of the user, the device, upon the under face thereof having longitudinally movable propellers designed to be operated by movement of the feet of the user, the said propellers, when projected in a forward direction being automatically folded so as to offer small resistance to the water, but when propelled in a 30 rearward direction, the same will open and offer a great resistance to the water so that 35 the user may, with comparatively small effort make rapid progress through the water, the device being of a buoyant nature to insure the non-sinking thereof and through the medium of its keel being insured 40 against tilting regardless of the roughness of the water in which the same is used.

45 A further object of the invention is to produce a device of this character which shall be of an extremely simple construction, cheap to manufacture, which may be easily and quickly applied to the person of the user and as readily detached, and which 50 will perform the functions for which it is devised with accuracy and with certainty.

55 Other objects and advantages will present themselves as the nature of the invention is better understood, reference being had to the accompanying drawings, in 60 which:

Figure 1 is a view illustrating the application of the improvement.

Fig. 2 is a bottom plan view of the improvement.

Fig. 3 is a sectional view approximately 60 on the line 3—3 of Fig. 2.

Fig. 4 is a detail sectional view through one of the propellers, showing the manner in which the same automatically opens when offering resistance to the water and automatically closing when subject to the resistance of the water.

Fig. 5 is a sectional view approximately 65 on the line 5—5 of Fig. 3.

The improvement contemplates the employment of a flat body member 10, substantially rectangular in shape and of a buoyant nature. If desired, the body 10 may have secured to its edges inflated bags or sacks 11 to add to the buoyancy thereof. On the 70 outer or upper face of the body 10 are secured straps 12 which have their ends adjustably connected as indicated by the numerals 13 and these straps are designed to be arranged around the body of the user 75 to secure the improvement thereon. Centrally secured to the outer or lower face of the body 10, of a length equaling that of the body, and arranged at a right angle with respect to the body is a keel 14. The keel 80 is preferably in the nature of a flat board of wood and is buoyant. The keel, at the front end of the body has a transverse opening therethrough indicated by the numeral 15, and in this opening is arranged a 85 grooved wheel or sheave 16 that preferably has its shaft or trunnions journaled in anti-frictional bearings.

90 On the under face of the body 10, near the edges thereof, but disposed a suitable 95 distance inward of the outer edge of the said body are depending right angularly disposed posts 17. The posts may be hollow or may be constructed of wood, it being essential that the said post be of a buoyant 100 nature. The posts are of a comparatively short length, and therefore are of a comparatively small weight. The posts have arranged thereon grooved or sheave wheels 19, and around these wheels 19 and around 105 the sheave wheel 16 is trained a cable 20. This cable has its ends disposed a considerable distance outward of the rear end of the body 10, and on the ends of the said cable are secured stirrup members 21—21. 110

Secured on the parallel end strands of the cable, a suitable and desired distance inward of the stirrups 21 are propellers 22-22. Each of these propellers includes 5 a body member 24 that is secured directly to the strands of the cable, and hingedly connected to the opposite sides of the body at the ends thereof nearest the stirrups are wings 24 and 25 arranged in opposite pairs. 10 On the body 23 are suitable stop members 26 to limit the outward swinging of the wings 24 and 25.

The device is strapped on the body of a person who is either in danger of drowning 15 or who is not an expert swimmer and desires to enter deep water. The feet of the user are arranged in the stirrups 21. The device being arranged upon the trunk of the user does not interfere with the free use of 20 his arms or legs, and consequently his arms may be employed for guiding and his feet employed for propelling. By moving his feet forward and backward, after being arranged in the water the propellers 22 will be reciprocated longitudinally. A forward 25 movement of the propellers incident to the contact thereof with the body of water in which the device is arranged, will cause the same to swing together or to close, but a 30 rearward movement of the propellers will cause the wings to open, thus permitting the said wings contacting with the water to offer a determined resistance thereto, permits of the device being rapidly propelled 35 through the body of water. The keel insures the device against tilting so that the same may be used with perfect safety in rough waters. The air bags, while not an absolute necessity, materially aid in buoy- 40 ing the body. The improvement is compar- atively small in size and may be stored in a stateroom or cabin of a vessel without oc- 45 cupying much space. The device may be readily attached to the person of a user and may be employed, as stated, either as a life preserver or as an assistance in swimming.

Having thus described the invention, what is claimed as new, is:—

1. In a device for the purpose set forth,

a buoyant body having means for attaching 50 the same to the trunk of a person, a keel centrally arranged on said body, a cable ar- ranged in guides on the under face of the body, stirrups on the ends of the cable, and propellers on the longitudinal strands of the 55 cable.

2. In a device for the purpose set forth, a buoyant body having means for attaching 60 the same to the trunk of a person, a keel centrally arranged on said body, a cable ar- ranged in guides on the under face of the body, stirrups on the ends of the cable, and collapsible propellers on the longitudinal 65 strands of the cable.

3. In a device for the purpose set forth, a 65 buoyant body having means for attaching the same to the trunk of a person, a keel centrally arranged on said body, a cable ar- ranged in guides on the under face of the body, stirrups on the ends of the cable, pro- 70 pellers on the longitudinal strands of the cables, each of said propellers including a flat body having flat wings hingedly connected to the ends thereof, and means be- 75 tween the body and wings for limiting the outward swinging of the wings with respect to the body.

4. In a device for the purpose set forth, a buoyant body member, detachable air bags 80 on the edges thereof, a depending keel on the outer face at the center of the body, de- 85 pending posts adjacent to the sides and in- ward of the outer edge of the body, sheave wheels on the posts, the keel at the outer end thereof having an opening therethrough, a sheave wheel therein, a cable guided around 90 said sheave wheels, stirrups on the ends of the cable, propellers on the longitudinal strands of the cable, and each of said pro- 95 pellers including hinged wings designed to be brought to an open position when the cables are moved outward of the body and to be closed when the cable is moved inwardly of the body, and means for limiting the outward movement of said wings. 95

In testimony whereof I affix my signature.

NELSON P. JOHNSTON.
